US00D884538S

(12) **United States Design Patent** (10) Patent No.: **US D884,538 S**
(45) Date of Patent: **** May 19, 2020**

(54) **ENTRANCE MACHINE**

(71) Applicant: **HANGZHOU HIKVISION DIGITAL TECHNOLOGY CO., LTD.**, Hangzhou (CN)

(72) Inventors: **Fan Wang**, Hangzhou (CN); **Xinqiang Ren**, Hangzhou (CN); **Wei Feng**, Hangzhou (CN); **Yepeng Chen**, Hangzhou (CN); **Kaicheng Ying**, Hangzhou (CN)

(73) Assignee: **HANGZHOU HIKVISION DIGITAL TECHNOLOGY CO., LTD.**, Hangzhou (CN)

(**) Term: **15 Years**

(21) Appl. No.: **29/707,878**

(22) Filed: **Oct. 1, 2019**

Related U.S. Application Data

(62) Division of application No. 29/641,639, filed on Mar. 23, 2018, now Pat. No. Des. 876,268.

Assistant Examiner — Katrina N Gonzalez

(74) *Attorney, Agent, or Firm* — Norton Rose Fulbright US LLP

(57) **CLAIM**

The ornamental design for an entrance machine, as shown and described.

DESCRIPTION

FIG. 1 is a front view of an entrance machine according to our new design; and,

FIG. 2 is a perspective view of the entrance machine shown in FIG. 1.

Back view, left view and bottom view of the design are omitted because these sides of the design are flat and unornamented.

1 Claim, 2 Drawing Sheets
